(51) LOC (7) Cl. **11-01**

CLAIM

The design for a natural gemstone, artificial gemstone ornamental object made of glass, as shown and described.

DESCRIPTION

FIG. 1 is a bottom view of a natural or artificial gemstone or ornamental object made of glass according to a first embodiment of the present invention;

FIG. 2 is a side view taken from the lower side of FIG. 1; FIG. 3 is a side view taken from the upper side of FIG. 1; FIG. 4 is a top view of the first embodiment;

FIG. 2 is a side view taken from the right side of FIG. 4; FIG. 6 is a side view taken from the left side of FIG. 4;

FIG. 7 is a bottom view of a natural or artificial gemstone or ornamental object made of glass according to a second embodiment of the present invention;

FIG. 8 is a side view taken from the lower side of FIG. 7; FIG. 9 is a side view taken from the upper side of FIG. 7; FIG. 10 is a top view of the second embodiment;

FIG. 11 is a side view taken from the right side of FIG. 10; and,

FIG. 12 is a side view taken from the left side of FIG. 10.
